UNITED STATES PATENT OFFICE.

EMERY R. NABORS, OF SAN ANTONIO, TEXAS, ASSIGNOR OF ONE-HALF TO THOMAS E. BREED, OF SAN ANTONIO, TEXAS.

ADVERTISING DEVICE.

Application filed August 18, 1925. Serial No. 51,059.

This invention relates to advertising devices and has for one of its objects to provide a device of this character which will be simple in construction, comparatively inexpensive to manufacture and which will prove quite efficient in attracting attention.

A further object of the invention is to provide an advertising device embodying a toy airship or other analogous apparatus, which may be readily set up in a show window, for example, and which through various elements associated therewith will simulate a machine which it represents.

A still further object of the invention is to provide an advertising device of the character described which may be self propelled and which will also incorporate a toy machine gun, for example, as well as an electrically flashing sign.

With the above and other objects in view which will appear as the description proceeds, the invention consists in the novel details of construction and combinations and arrangements of parts more fully, hereinafter described and particularly pointed out in the appended claims.

Referring to the accompanying drawings, forming a part of this specification in which like reference characters designate like parts in all the views;

Fig. 1 is an elevational view of an advertising device constructed in accordance with the present invention;

Fig. 2 is a top plan view of the same;

Fig. 3 is a side elevational view partly broken away, of the toy aeroplane illustrated in Fig. 1;

Fig. 4 is an enlarged vertical sectional view through a portion of the supporting arm;

Fig. 5 is a horizontal sectional view taken approximately on the plane indicated by the line 5—5 of Fig. 4; and,

Fig. 6 is an enlarged plan view of the rotary circuit making and breaking apparatus for controlling certain of the electric circuits.

Referring more particularly to the said drawings, numeral 10 indicates any suitable

support, as for example, a beam or plank 50 which is provided with a hole 11 extending therethrough and through which passes one end of a tubular supporting arm 12. The said arm 12 is rotatably mounted by means of anti-friction bearings 13 and 14, 55 in a pair of housing members 15 and 16 which are clamped on opposite sides of the support 10 by suitable clamping bolts 17. The tubular arm 12 has rigidly mounted upon it, a pair of contact rings 18 and 19 60 which are electrically insulated from the said arm by the bushings or sleeves 20, which rings are adapted to be engaged by a pair of brushes, 21 and 22, carried by suitable brush holders 23 and 24, respectively, 65 mounted within the housing members 15 and 16. The brush holders 23 and 24 are respectively connected by means of wires 25 and 26 to any suitable source of electrical current not shown. 70

The other end of the tubular arm 12 is provided with a swivel connection 30 which carries a cross arm 31 which in turn carries a pair of smaller tubular members 32 which are preferably curved substantially as 75 shown in Fig. 2. These curved members 32 in turn are connected in any suitable manner to the particular device selected for the advertising novelty, here shown as constituting a toy aeroplane 33. 80

Within the fuselage of the plane there is mounted a small electric motor 34, the shaft 35 of which carries a suitable propeller 36 as will be clear from the drawings. 85

Upon the top of the fuselage there is preferably provided a small replica of a machine gun indicated by the numeral 37 and also a rearwardly extending tube or pipe 38 intended to simulate an exhaust pipe for example, of an aeroplane motor. The machine 90 gun 37 is provided with a small electric lamp 39 which is adapted to be flashed on and off alternately by the circuit making and breaking apparatus, to be later described, and the said tube 38 is likewise provided 95 with one or more such lamps 40, which are also controlled by the circuit making and breaking apparatus. The side walls of the

aeroplane fuselage are also preferably perforated as indicated at 41, the perforations taking the form of letters constituting a sign, which letters are also illuminated by suitable lamps 42, likewise controlled by the circuit making and breaking apparatus.

The contact ring 18 above described is electrically connected to a conductor wire 45 which may constitute a common feed 10 wire for the motor 34 and for the various electric lamps above described. In like manner the contact ring 19 has connected to it, a wire 46 which serves as a common return wire for the various electric devices.

15 The circuit-making and breaking apparatus above referred to is preferably of the rotary type and is somewhat similar to the usual drum commutator, in that it comprises a disc or member 50 of insulating material, 20 the outer circumference of which has set into it a plurality of conducting bars or segments 51, each of which is connected by a wire or conductor 52 with the wire 45, which as was above mentioned, constitutes a common feed wire for the various devices. A 25 pair of brush members 53 and 54 are suitably mounted upon the housing member 15 and engage the circumference of the disc member 50, sliding thereon, as the latter is 30 rotated, whereby they are alternately made to contact with the conducting segments 51 and the insulating portion between said segments, as will be readily understood from Fig. 6. The brush 53 is connected by the 35 wire 55 to the light 39 in the machine gun 37, while the brush 54 is connected by a wire 56, to the lights 40 in the exhaust tube and 42 in the fuselage, which latter lights serve to illuminate the sign letters 41. Each of 40 these lights 39, 40 and 42 is connected by a suitable wire to the common return wire 46 above mentioned, as will be readily understood.

The operation of the advertising device 45 will be clear from the foregoing, it being understood that current passing from a source not shown, through the wires 25 and 26, will be transmitted through the brushes 21 and 22 to the contact rings 18 and 19 and 50 through the medium of the wires 45 and 46, directly to the motor 34. The rotation of the armature of this motor will, of course, produce a like rotation of the propeller 36 which will have the effect of driving 55 the plane through the air in a circle, the arm 12 freely rotating upon the anti-friction bearings 13 and 14. During such rotation, the disc member 50 and the conducting segments 51 will be rotated past the rotating 60 brush members 53 and 54, alternately making and breaking the circuits to the lights 39, 40 and 42, and causing them to flash in the well known manner. The flashing of the 65 light 39 will produce a good imitation of the firing of a machine gun, while the flashing

of the light 40 will simulate the exhaust of the aeroplane motor.

As shown in the drawings, the brushes 53 and 54 of the circuit making and breaking device are diametrically opposed and since 70 an even number of conducting segments has been illustrated the various lights 39, 40 and 42 will be illuminated and extinguished simultaneously. It will be obvious, however, that by shifting one of the brushes 53 or 54 a slight distance circumferentially so that it will rest upon an insulating portion while the companion brush rests upon a conducting segment, that the said lights may be caused to flash alternately instead of simultaneously. In like manner, the same result 75 might be accomplished by making the number of conducting segments 51 odd instead of even.

For purposes of illustration only, an aeroplane has been shown in the drawings and it will be understood that any other suitable form of toy device, such for example as a dirigible, balloon, automobile, tank and the like might be substituted therefor, without departing from the scope of the invention.

While one form of the invention has been illustrated and described, it is obvious that those skilled in the art may vary the details of construction as well as the precise arrangements of parts without departing from the spirit of the invention, and therefore, it is not wished to be limited to the above disclosure, except as may be required by the 100 claims.

What I claim is:

1. In an advertising device of the character described, a support; a housing carried by said support; a bent tubular arm rotatably mounted in said housing; insulated conductor rings carried by said arm within said housing; brush members carried by said housing engaging said rings; a toy device provided with a propelling motor, carried by said arm; electrical connections carried within said arm, between said rings and motor; a plurality of sets of lamps carried by said toy device; an electrical circuit maker and breaker carried by said arm adapted to intermittently flash said sets of lamps; and electrical connections, also carried within said arm, between said breaker and said sets of lamps.

2. In an advertising device of the character described a support; a housing carried by said support; a bent tubular arm, one end of which is rotatably mounted in said housing; insulated conductor rings carried by said arm within said housing; brush members carried by said housing, engaging said rings; a toy airship carried by the other end of said arm; an electric motor carried by said ship; a propeller actuated by said motor; electrical connections carried within said arm, between said rings and

motor; a toy machine gun provided with a lamp, carried by said ship; an exhaust pipe provided with a lamp, also carried by said ship; characters constituting a sign, and a lamp for illuminating them, also carried by said ship; an electrical circuit maker and breaker comprising a rotatable member car- ried by said arm and additional brushes carried by said housing, for intermittently flashing said lamps; and electrical connections also carried within said arm, between said breaker and said lamps.

In testimony whereof I affix my signature.
EMERY R. NABORS.
